CHESTER A. DE LABAR.

INVENTOR.

By George J. Oltsch
ATTORNEY.

UNITED STATES PATENT OFFICE.

CHESTER A. DE LA BAR, OF GRAND RAPIDS, MICHIGAN.

OIL-CAN.

1,198,115.

Specification of Letters Patent. Patented Sept. 12, 1916.

Application filed July 19, 1915. Serial No. 40,669.

To all whom it may concern:

Be it known that I, CHESTER A. DE LA BAR, a citizen of the United States, residing at Grand Rapids, in the county of Kent and 5 State of Michigan, have invented certain new and useful Improvements in Oil-Cans, of which the following is a specification.

My invention relates to improvements in oil-cans, and more particularly to the means 10 employed for securing the caps used for effecting a closure of the inlet and discharge openings, so as to prevent the loss or misplacement of the same.

A further object of the invention resides 15 in the provision of means whereby the closure caps are yieldingly held in position over the inlet and discharge openings so that they may be easily and quickly removed and replaced, and to provide a simple structure 20 for the purpose stated which is easily applied, effective in operation, and cheap of manufacture.

With these and other objects in view, the 25 present invention consists in the combination and arrangement of parts hereinafter more fully described, illustrated in the accompanying drawings, and particularly pointed out in the claims, it being understood that minor changes may be made in the 30 details of construction without departing from the spirit or sacrificing any of the advantages of the invention.

In the accompanying drawings which 35 show the preferred embodiment of my invention: Figure 1 is a top or plan view of a receptacle embodying the features of my invention. Fig. 2 is a side elevation of the upper end of a receptacle, showing the closure caps seated in full lines and unseated 40 in dotted lines. Fig. 3 is a side elevation of the cap for the inlet opening.

Referring to the drawings, the receptacle 5 is provided with the usual spout 6, for discharging the contents therefrom, and 45 which is hereinafter referred to as the discharge opening, and a flanged inlet opening 7, used for filling the receptacle.

Mounted upon the receptacle between the discharge and inlet openings, is a bracket 8, 50 comprising the leg members 9, and a cross-rod 10, connecting the upper ends of the legs. The means employed for securing and holding the caps in place consists, preferably, of a single strand of spring wire 11, 55 which is doubled upon itself in spaced relation, with its bight portion 12, extending

slightly beyond the inlet opening. The opposite members thereof are then coiled near their ends around the cross-rod 10, of the bracket, and the ends 13 extend to a point 60 at opposite sides of and adjacent the central portion of the spout. When thus formed and mounted, the spring member has a downward tension at the free ends of its oppositely extending arms. A closure cap 65 14, is adapted to fit over the end of the discharge opening, and is pivotally mounted at the end of and between the spaced arms of a U-shaped link member 15, the ends of which are in turn hingedly connected at 16, 70 with the ends of the spring arms 13. The spring arms 13, owing to the downward tension thereof, yieldingly hold the cap in place, and permit same to be easily removed by raising the cap against the tension of 75 said arms. The cap is shown in and out of position by full and dotted lines in Fig. 2. The closure cap 17, for the inlet opening, is slidingly connected with and disposed between the opposite parallel members 18, of 80 the spring. A handle 19, consisting of a looped wire, has its ends extending down the sides of the cap and bent so as to pass around the spring members, thus connecting the cap to the spring members and allowing 85 the same to freely slide thereon. The bight portion of the spring, indicated at 12, limits the movement of the cap in one direction, and the bracket supporting the spring limits its movement in the opposite 90 direction, so that at no time is the cap detached from its connections, and the danger of loss or misplacement thereof is obviated. In order to remove the cap, the same is raised against the tension of the spring 95 until it clears the flange of the opening, when it is shifted to one side and allowed to rest upon the top of the receptacle, as indicated by dotted lines in Fig. 1. The cap is thus entirely out of the way, and as the 100 bight portion of the spring passes around the flange of the opening, access to the opening is entirely unobstructed. Either cap may thus be easily and quickly removed or replaced, and as they are never wholly 105 detached from their connections, they cannot become lost or misplaced.

Having thus described my invention, what is claimed is:

1. The combination with a receptacle 110 having inlet and discharge openings, of closure caps for said openings, a spring

member mounted between said openings and having oppositely extending arms, means connecting said spring arms and caps, the cap for the inlet opening having a sliding connection with its spring arm to permit same to be shifted bodily relatively thereto.

2. The combination with a receptacle having an inlet opening, of a spring member mounted thereon and having a downward tension, and a cap for said opening having connection with and slidably upon said spring member to permit same to be raised from its seat and bodily shifted to one side of the opening.

3. The combination with a receptacle having inlet and discharge openings, of a spring member mounted thereon having oppositely extending arms, a cap for the discharge opening hingedly connected with the spring arm extending in one direction, and a cap for the inlet opening having a

sliding connection with the oppositely directed arm, whereby said cap may be bodily shifted to one side of said opening.

4. The combination with a receptacle having inlet and discharge openings, of a spring member composed of a wire strand bent in spaced parallel relation, its opposite legs coiled around a bracket mounted between the openings and terminating at opposite sides of and adjacent the discharge spout, a cap for the discharge opening hingedly connected with said terminals, and a cap for the inlet opening disposed between and slidably connected with the spaced legs of the spring.
